PHASE SHIFTER

Andrew Alford, New York, N. Y., assignor to
 Mackay Radio and Telegraph Company, New
 York, N. Y., a corporation of Delaware

Application February 14, 1942, Serial No. 430,899

6 Claims. (Cl. 178—44)

This invention relates to phase shifters and more particularly to phase shifting arrangements in which networks or two or more units are provided to effect the phase shift.

In my prior Patent 2,147,807 is shown a system using two inductive or capacitive elements arranged with respect to one another, providing a unit to produce a desired phase shift in a two-conductor line. My prior Patent No. 2,276,910, issued March 17, 1942, shows similar phase shifting units consisting of two condensers in a single conductor line such as an antenna.

It is frequently desirable to obtain a greater phase shift than can conveniently be accomplished by one of these phase shifting units. Two such units may give sufficient phase shift but the additional weight of so much added apparatus may be objectionable.

According to my invention the last named difficulty may be overcome by arranging two phase shifting units, such as disclosed in my prior patent or application, in a line so that the adjacent elements of each phase shifter are superposed. Thus, the combined effect may be achieved with three properly spaced elements, the center one having the combined characteristics of the other two.

If two condensers are normally used for each phase shifter, the center condenser of the combined units, formed to have the combined effect of the others, will be equal in value to the series capacity of the two outside condensers. In the case of equal condensers this will be half the capacity of one outside condenser.

A better understanding of my invention will be had from the particular description thereof made with reference to the accompanying drawings, in which

Figs. 1 and 2 are used to explain one embodiment of my invention;

Fig. 2A shows a modified form of my invention;

Fig. 3 illustrates a practical radio system using a phase shifter in accordance with my invention; and

Figs. 4 and 5 illustrate embodiments of my invention applied to two conductor transmission lines.

In my prior Patent 2,147,807 is described an arrangement in which impedance elements may be arranged in a line in conjugate relationship. This conjugate relationship is such that the phase of wave energy transmitted along the line may be altered without altering any of the other characteristics of transmission of these waves.

In order to secure this conjugate relationship of network elements as taught in that patent, two elements are provided and the spacing between these elements is adjusted, and the location along the line chosen with respect to the maximum of standing waves in the line to achieve the desired results. The complete mathematical derivation of the proper spacing, location, and impedance characteristics of the units for use in this system is set forth in that patent and need not be repeated here.

In the patent referred to above, the impedance units are all shown related to two conductor transmission lines and are bridged across this line. It is clear, however, that the relationship set forth therein is equally applicable to single conductors and my prior Patent No. 2,276,910, issued March 17, 1942, illustrates a special application of condenser impedances used in single conductor lines which in this instance are preferably antenna conductors.

It frequently occurs that a greater phase shift than is normally produced by a pair of conjugately related impedances is desired. In such cases two or more of such arrangements may be provided in the line to achieve this result. Such an arrangement is shown in Fig. 1, in which a single line L is provided with two sets of reactance units C1, and C2, arranged in conjugate relationship. It is evident, however, that such an arrangement doubles the weight which must be supported by the wire since it requires two additional impedances. In accordance with my invention this additional weight may be reduced by moving the two conjugate networks together so that the adjacent condensers of each conjugate unit are superposed. Such an arrangement is shown in Fig. 2. In this instance since C1 and C2 at the center part of the complete network are combined to form a single condenser unit C3, the equivalent impedance effect of the two units is combined in the single condenser C3. This results in a condenser C3 smaller in size than condensers C1 and C2, since the impedance of this unit must be the combined impedance of the other two.

For all single conductor lines it is preferable to use capacitive reactances as the conjugate impedance element, since in the single conductor line the units are arranged in series in the lines and thus the capacitive elements when combined will be smaller than the sum of the two units. As is well known, the sum of series connected capacitive reactances is such that the reciprocal

of this sum is equal to the sum of the reciprocals of the other units. Accordingly, in the arrangement of Fig. 2,

$$\frac{1}{C_3} = \frac{1}{C_1} + \frac{1}{C_2}$$

As a general rule C_1 and C_2 are equal, so that C_3 is then equal to one-half of C_1 .

The particular application of this arrangement to an antenna structure is shown in Fig. 3. In this figure a radio translator arrangement 3, which may be either a transmitter or receiver, is shown connected to a V-type antenna comprising two sections 4, 5 and two other sections 6, 7. In order to obtain the desired phase shift between elements 4, 5, a phase shifting network consisting of condensers C_1 , C_3 , C_2 , is shown, and a similar arrangement C_{1a} , C_{3a} , C_{2a} , is shown between sections 6 and 7.

It should be clearly understood that while condenser units of this type are generally preferred, single conductor transmission lines may use other forms of impedances. In Fig. 2A is shown a transmission line in which line L is provided with short sections of short circuited transmission lines to induce the desired impedance. These sections are shown as S_1 , S_2 and S_3 . As is well known, if the transmission line sections are made shorter than a quarter of a wavelength long, the effective impedance will be capacitive, while if they are made greater than a quarter of a wavelength long the effective impedance will be inductive. In any case the impedance of S_3 is made equal to the sum of the impedances of S_1 and S_2 . In such transmission line sections the known formula for deriving the impedance of transmission lines may be applied to secure the right length for the center section with respect to the outer sections. Likewise, the spacing between the units must be proper to preserve the conjugate relationship as in the manner outlined in my previously mentioned Patent 2,147,807.

It is also clear that lumped impedances such as inductive elements may be used if desired although this is generally not preferred in single conductor transmission lines.

In Fig. 4 is illustrated a further embodiment of my invention as applied to two-conductor transmission lines. In this figure is shown a transmission line consisting of conductors 40, 41, across which are bridged impedance elements 43, 44, 45, each consisting of a short circuited transmission line section. It is clear that if desired other forms of transmission line section may be used, such as open-ended sections, properly adjusted in length to give the desired impedance value. Since these impedance elements are arranged in parallel across the transmission line instead of in series in the line, the use of inductive values rather than capacitive values is preferable. If bridged capacities are used, then the central element 44 would have to be equal or equivalent to twice the capacity of the other two elements necessitating a larger structure. However, when inductive elements are bridged in this manner the parallel impedance of the central element will be equal to one-half the inductive impedance of either of the other elements 43, and 45 assuming these elements to be equal.

It can, therefore, be readily seen that in the case of parallel conductor connections, as thus shown, inductive impedances are preferable to capacitive impedances.

5 Instead of the use of transmission line sections, as shown in Fig. 4, lumped impedances such as shown at 53, 54 and 55, may be provided. It is clear that in place of the inductances 53, 54 and 55 capacitive units may be provided, but in general this is not desirable when shunt connections are used, for the reasons outlined above.

10 It should also be clear that in the case of the two-conductor transmission line, such as shown in Figs. 4 and 5, the series arranged impedance system of Figs. 2 and 2A, may be used if desired instead of the shunt connected impedances. In this case, however, these impedance elements must be provided in each of the lines 40 and 41. This is generally not desirable since it is then necessary carefully to check both of the units as applied to the line to secure equal effects in both sides.

15 While I have described the features of my invention with reference to certain specific embodiments thereof, it should be clear that many alterations and changes may be made without departing from the spirit of my invention. For example, any of the types of units shown or mentioned herein may be used in either two-conductor or single conductor transmitting arrangements. 20 Furthermore, the systems may be used in other types of antenna structures or in any arrangement of transmission line that is desired.

25 What is claimed is:

30 1. A phase shifting network for a conductor line comprising three impedance elements arranged in spaced relation connected to said line, the spacing between each two adjacent elements being such as to produce conjugate relationship, the centrally arranged impedance having a value substantially equal to the effective sum of the impedance values of the outer two impedance units.

35 2. A phase shifting network according to claim 1, wherein said impedance elements are condensers.

40 3. A phase shifting network according to claim 1, wherein said line is a two-conductor transmission line, said impedance elements being connected across said line.

45 4. A phase shifting network according to claim 1, wherein said line is a single conductor line, said impedance elements being effectively in series in said transmission line.

50 5. A phase advancing network for a single conductor line, comprising three condensers connected in series in said line, the spacing between each two adjacent condensers being such as to produce conjugate relationship, the centrally arranged condenser having a capacity substantially equal to the effective series capacity of the two outer condensers.

55 6. A phase advancing network according to claim 5, wherein the outer condensers of said phase shifter have equal capacities the central condenser having a capacity equal to one-half of the said equal capacity.

60 ANDREW ALFORD.
